APPARATUS FOR THE SEPARATION
OF ACID AND METAL

Raymond L. Lunt, Valencia, Pa.

Application September 20, 1946, Serial No. 698,383

2 Claims. (Cl. 204—212)

1

This invention relates to a process and apparatus for the separation of acid and metal and is herein illustrated in some detail as applied to the recovery of pickling acid from the spent acid of a strip steel pickling plant, but certain features are adapted to be used for the production of extremely pure metal with the incidental recovery of acid with which the metal is combined.

In the pickling of metals, particularly of steel, iron and brass, large quantities of acid, usually sulphuric acid are used, and these acids gradually become contaminated or weakened, or become syrupy from contained salts, until they have to be withdrawn from use. In the past these withdrawn acids have been largely wasted, sometimes they have been simply dumped into streams, often contrary to law. Sometimes they have been neutralized with metal or even with lime and used for the production of ferrous sulphate or of venetian red, and these products have been sold below cost simply to get rid of them. The metal content of the acid wasted usually exceeds $\frac{1}{2}$ lb. of metal per gallon.

In many instances in the pickling of iron, fresh acid solution is added, carrying 15% by volume of anhydrous acid, and at the end the entire batch is ordinarily discarded and dumped, when the acid content has dropped to 10% by volume and the iron content has reached $\frac{1}{6}$ of a pound per gallon making the solution syrupy. Before this happens, ordinarily acid has been added to the solution to make up temporarily part of that used. In some plants it is customary to be adding acid all the time and to make up entirely new fresh acid solutions every 2 or 3 days, shutting down the pickling equipment, washing it out with fresh water, and running fresh water and fresh acid into the pickling tank, and heating the new acid mixture by steam to the usual pickling temperature.

According to the present invention the iron or other metal carried in the solution may be economically recovered, in the form of a very pure iron, in various states from powdered to solid forms, under favorable circumstances, so that it is useful for making special steel alloys, and for the making of pure anodes or iron.

According to the present invention, moreover, it is possible to keep the metal content of the pickling liquid low for a long period of time and to keep the acid content high. By this combination of high acid and low metal content it is possible to maintain a constant speed in pickling, avoid much of the syrupy handicap, and obtain

2

the uniform results desired without constantly adding acid or making up fresh solution at frequent intervals.

The present invention, moreover, recovers a useful acid and a useful metal thus removing the temptation to dump the pickling residues and thus removing the temptation to pollute the streams and lakes.

Attempts have hitherto been made to recover pickling acid both electrolytically and chemically, but they failed to provide for the easy and economical removal of the metals separated out. They involved the frequent cleaning out of clogged up cells and the breaking of short circuits formed within the cells. The cells often contained diaphragms and many of them allowed stray currents to enter the main pickling tank. The chemical devices for recovering pickling acid also involved serious difficulties in handling the recovered metal.

According to the present invention the foregoing and other difficulties and disadvantages are overcome and a cell is provided which needs no diaphragm, needs no added devices for prevention of stray currents, permits the cleaning of cells while the plant is in operation, reduces the consumption of labor, time and electricity, and collects the recovered metal in easily removable pails which when replaced readily seat themselves to form good electrical contacts within the cell and thus become an effectively electrically connected cathode.

In the form shown an insoluble anode rotates within the pail and is adapted to drop recovered metal on the bottom of the pail and is shown as provided with arms which rotate with it and which are adapted to knock off any electrolyte trees which may form.

The cells are preferably arranged so that the electric current goes through them in series, and the electrolyte also goes through them in series, with the result that the last cells receiving the electrolyte contain an electrolyte low in metal content and high in acid content and therefore produce loosely adherent granular deposits which may be of very pure metal and be separately collected if desired.

The series of cells are preferably so divided up that the current goes from the center of each series to the end of the series thus keeping the potential identical at each end of the device, with the result that no stray current tends to go through the pickling tank.

There are preferably at least 2 series of cells for recovery of metal and acid, so that the ap-

paratus may run continuously, one series being shut down to enable recovered metal to be removed while current is going through the other series of cells. One advantage of this lies in the fact that it also provides smaller cathode pails for collecting the metal so that they may be easily lifted by one man. Preferably the apparatus is so operated and designed that the pails may be removed when their weight does not greatly exceed 75 lbs. per pail, thus facilitating manual cleaning.

The economy of the present invention appears when it is realized that with fifty cells in series each kilowatt hour at 100 volts delivers about $7\frac{1}{2}$ amperes to a cell producing about 0.01725 pound of iron and about 0.02925 pound of acid per hour per cell. Thus one kilowatt hour produces from the series of cells 0.85 pound of iron and 1.45 pounds of acid.

Thus acid is produced for about 0.74 cent a pound at the common figure of one cent per kilowatt/hour for power, if the recovered iron pays for labor and overhead.

Theoretically, therefore, it will be cheaper to recover acid than to buy acid. In fact, the effective cost of the bought acid is much greater since the bought acid is usually discarded when one-third of the free acid in a pickle solution has been used up, whereas recovered acid is recovered in the pickling solution and none is discarded.

Moreover, the present process avoids many hazards involved in handling acid, avoids great expense in neutralizing waste acid, avoids frequent emptying and washing out of pickling tanks and avoids much of the cost of heating.

In many installations the first cost of fresh acid may be only about one-fifth of the cost of acid used plus expenses of handling and treating discard, most of which cost and expense the present invention eliminates.

Other features and advantages will hereinafter appear.

In the accompanying drawings:

Fig. 1 shows diagrammatically a pickling tank and attached recovery devices of the present invention and some other parts;

Fig. 2 is a diagrammatic cross section of a cell of the present invention.

In the form shown in some detail anode current comes through a flexible main 10 and delivers the current by a slip contact brush 11 to a vertical shaft 12 preferably covered with rubber 13 so that the current reaches the anode 14 shown as screwed on to the conductor 12.

The anode 14 is shown in the form of a ball immersed to about the center of the glass or stoneware cell 15. A fixed cathode member 16 is shown as projecting up from the bottom of the cell 15 through a rubber or other insulating plug 17 so as to support a removable pail 18 having nearly vertical sides 19 which rise well above the top of the anode 14. The cell 15 is shown as provided with an entrance pipe 20 (preferably a non-conductor rubber hose) near the cathode support 16 for delivering entering electrolyte horizontally into the cell 15 so that it tends to go between the three arms 21 of the cathode support 16 and enter the bucket 18 by means of an upstanding pipe 22 in the center of the bottom of the bucket. The pipe 22 is preferably an open top rubber nozzle fitting into an opening 23 in the bottom of the bucket 18 and rising higher than any deposit of metal is likely to form within the bucket 18.

The bucket 18 is also shown with a few bottom perforations 24 between the arms 21 through

which incoming electrolyte may enter the bucket 18. Preferably there are three arms 21 slanting upwardly and outwardly so that inwardly inclined bottom slopes 25, forming the bottom of the bucket, rest on the cathode support arms 21 even if it is placed hastily on them and somewhat off center. The bucket is also provided with openings 26 near its top through which electrolyte tends to flow out so that it passes off through an overflow pipe 27 at the top of the cell 15 and opposite from the inlet 20.

In the form shown the outlet pipe 27 is on the line with the openings 26 and the bucket top 28 is shown as high as the top of the pipe 27 and lying close to an internal rib 29 of the cell 15. The rib 29 may include an annular groove 29a so that outflowing electrolyte tends to come from the openings 26.

The rubber coating 13 of the anode shaft 12 may extend down well below the top of the bucket and carry arms 30 which will revolve with the revolving anode so as to break off any trees that tend to form on the cathode bucket with the result that they fall down and collect around the upwardly projecting pipe 22. The cathode conductor 31 which comes from a cathode member 16 is shown as becoming a flexible cable 32 coiled upwardly so as to be the anode main of the adjacent cell except for the last cell of the series. The cell 15 is shown as supported by a frame work 33 through intervening cushions 34.

When the cell has been operated long enough to accumulate considerable metal within the bucket 18, the drive for turning the anode 14, diagrammatically shown as a pulley 35, is swung upward as by pulling by a hoist ring 36 to lift the anode 14 out of the way and then the bucket 18 is lifted by handles diagrammatically shown as 37 inserted in some of the holes 26 and the bucket with its solid contents is removed after allowing the solution to drain out through the holes 24 and the bucket together with its contents is placed in a suitable dump for recovered metal. The plug 22 may be removed and placed 45 in a new bucket 18.

The bucket may be returned to the cell, or buckets may be provided of the same metal which is being deposited and the buckets may be discarded with their contents into the dump of recovered metal.

The recovered metal usually is in the form of powder or sponge falling from the surface of the cathode 19 and heaping up on the bottom of the pail 18 and is of great purity. Thus the 55 recovered metal provides a source of highly pure iron, for example, as soon as it is washed. No short circuits can form through the trees because the trees are broken off as soon as they are long enough to be hit by the revolving arms 60 30 and the recovered metal is not attacked by the acid of the electrolyte because the metal and bucket are in electrical contact with the cathode support 16.

Any small amount of metal which escapes 65 through the holes 24 against the incoming current of electrolyte settles in the bottom of the cell and is readily washed out by lifting the rubber plug 17 out of the bottom of the cell it being shown as tapered for the purpose so that 70 a hose may clean out the bottom of the cell.

The anode 14 in the recovery of acid procedures is preferably made of lead or a lead barium alloy so as to be insoluble or of some other acid-insoluble metal. If the cell is used for the 75 production of powdered metal, for which it is

well adapted, the anode 14 should be of large size and of soluble metal for best results and higher current densities ordinarily should be used.

For the recovery of acid, and where recovery of the metal is of less importance, it is possible to increase the conductivity of the cell by the addition of sulfate of alumina or alum to the solution. This cuts down the evolution of hydrogen and allows a much greater proportion of the iron sulfate to be regenerated into acid.

The arrangement of cells and other devices shown in Fig. 2 enables recovery of pickling acid to be accomplished safely and economically. In the form shown in this figure, strips of metal such as iron travel through a long tank 40 carrying the pickling acid and the pickling acid is maintained hot by withdrawing acid at a pipe 41 near the exit end 42 from which the sheets of iron are delivered and the pipe 41 delivers the acid to a motor pump 42 which forces it through a heat exchanger 43. The heat exchanger delivers the acid back into the tank 40 through a pipe 44 near the point where the sheets of metal enter the tank.

In the form shown the acid of the tank is also continuously circulated by withdrawing acid through a pipe 45 near the end 42 by means of a pump 46 and delivering it to the first cell 47 of one series of cells or the first cell 48 of another series of cells 14 so that the acid flows from the cell 47 through all the cells 15 of that series to the last cell 49 and thence through a pipe 50 into the tank 40 near the entering hot acid 44.

The current for operating the cells 15 of each series is shown as generated in a motor generator 51 so as to deliver positive current to the center conductor 52 of either the cells of series 47 or the cells of the series 48. The end cells 49 of each series is shown as connected by a main 53 to the negative terminal 54 of the generator 55 and the first cells 47 and 48 are likewise shown as connected to the negative terminal 54 by a main 56. These connections provide identical potentials at opposite ends of the pickling tank 40 and so prevent any waste of current or side current going through the tank 40.

In order to enable the buckets above described to be held safely, a separate switch 58 and a separate switch 59 is provided for each end cell 49 of the series and separate switches 60 and 61 are provided for the end cells 47 and 48 and separate switches 62, 63, 64 and 65 are provided between the positive conductor 66 and each half of each series of cells at the center 52.

Generally the cells will lie in a series of 50 to 56 cells with a shunt wound generator of 125 volts.

It will be seen that there is provided a type of cell which collects cathode deposit in easily removable units, handled safely, and adapted to center themselves in good electric contact with the cathode members that no diaphragms are needed and the cell itself is easily cleaned of any deposit which interferes with its proper operation. The equipment avoids the production of stray currents, enables the cells to be used for the production of metal powders or the recovery

of acid at will. In operating a pickling acid recovery plant the stronger acid is inserted where it is readily heated and works most efficiently. Moreover, the cells are so designed that any part is easily replaceable and the whole procedure is easily controlled. Since the acid is recovered continually the acid content of the pickling bath will average much higher, if desired, than in the pickling baths which have hitherto been maintained by intermittent additions of fresh acid. In the alternative the acid may be kept nearly free from salts and, being non-syrupy, will function in some ways as if strong. Moreover, the by-product recovery metal such as iron is of extraordinary purity and ordinarily well worth recovering at a high price.

The slight loss of acid in recovering and emptying the buckets is easily made up and is trivial compared to the loss of acid in past procedures. The number of series of cells may be as great as desired so that one can always be cleaned, while the other series are being used for acid regeneration and metal recovery.

Having thus described one form of the invention in some detail, what is claimed is:

1. A circulating cell for acid separation including an acid resisting rotatably mounted anode, a conducting cathode support below the anode, a bucket cathode resting on the support and receiving its current therefrom and surrounding the anode, pipes opening into the cell for delivering acid bearing salt solution to the bottom of the cell and removing acid from its cell at the top, and an arm on the anode rotating with it and extending over substantially the height of the submerged anode and spaced from both anode and cathode and adapted to break any trees on the cathode before they reach the anode.
2. A circulating cell for acid separation including an acid resisting rotatably mounted anode, a conducting cathode support below the anode, a bucket cathode resting on the support and receiving its current therefrom and surrounding the anode, pipes opening into the cell for delivering acid bearing salt solution to the bottom of the cell and removing acid from its cell at the top, and non-conducting arms on the anode rotating with it and extending over substantially the height of the submerged anode and spaced from both anode and cathode and adapted to break any trees on the cathode before they reach the anode.

RAYMOND L. LUNT.
